UNITED STATES PATENT OFFICE

FRITZ TAUSCHER, OF OBERLUNGWITZ, GERMANY

JACK SINKER OF SPECIAL SHAPE FOR KNITTING FRAMES

Application filed December 5, 1927, Serial No. 237,705, and in Germany January 8, 1927.

It has been proposed to make jack-sinkers of knitting frames with a short nose and shorter front-part for reducing the distance through which the sinker has to travel in its reciprocatory movement, thereby increasing the efficiency of the knitting-machine.

It has further been proposed to arrange the point of the sinker-nose farther back than usual, but in this case however the boundary-line of the sinker-nose is so steep that the weals are not properly held, and therefore sometimes loops are slipped with the result that the fabric produced is defective.

According to the invention the point of the sinker-nose is disposed farther back than usual but the boundary-line of the nose, instead of being a straight line, is a broken or curved line, the lower portion of which has the same inclination as the front edge of an ordinary jack-sinker.

An embodiment of the invention is illustrated, by way of example, in the accompanying drawing, in which:

Fig. 1 shows a side-elevation of the improved sinker.

Fig. 2 is a side-elevation, showing the head of the improved sinker on an enlarged scale.

The front-portion of ordinary sinkers is so long that the thread-guides deposit the thread in front of the point 1 of the nose 2 of the jack-sinker and the front-portion still stands between the needles 3 of the knitting frame, when the sinker is in the retracted position. The effect of this is to produce a definite path from x to y .

In order to reduce this path of travel it has been proposed, to make the boundary-line of the sinker-nose steeper, i. e. to place the nose 2 farther back. This form of construction has the disadvantage however that the sunk loop does not have sufficient hold on the steep edge 5 and slips upward so that the fabric becomes defective. This construction has consequently not been adopted.

According to the invention the point 1 of the sinker-nose is also placed farther back, but the boundary-line of the nose is curved or broken so that the upper portion 5' being somewhat steep, and the lower portion 5" being inclined in a rearward direction in

relation to the part 5 so that the loop finds sufficient hold on said lower part 5".

The front part 6 of a sinker which has a nose of this shape, is shortened accordingly, and the distance over which the sinker travels is reduced by the distance which the point 1 of nose 2 is set back. Owing to this reduction in the distance to be traveled, the frame can be run more rapidly, as each sinker has to travel twice forward and twice backward to form one loop, so that the travel is reduced four times the distance of which the point 1 is placed farther back. The inclined portion 5" of the front of the nose prevents displacement of the weals. The efficiency of the machine is considerably increased.

I claim:

Jack sinker for knitting frames in which the boundary line of the upper sinker-nose from the throat down to the front nose-point is so formed that the lower portion of said boundary line is inclined at a lesser angle to the lower edge of the sinker than the upper portion along the corresponding section.

In testimony whereof I affix my signature.

FRITZ TAUSCHER.
